Primary Examiner — Kendra Leslie Hamilton

(74) Attorney, Agent, or Firm — Davis Wright Tremaine LLP

(57) CLAIM

The ornamental design for a set of animal boots as shown and described.

DESCRIPTION

FIG. 1 is a perspective view of a set of animal boots showing an embodiment of our new design;

FIG. 2 is a front view thereof;

FIG. 3 is a back view thereof;

FIG. 4 is a right-side view thereof;

FIG. 5 is a left-side view thereof;

FIG. 6 is a top view thereof;

FIG. 7 is a bottom view thereof; and,

FIG. 8 is another perspective view of the set of animal boots showing our new design being worn by a dog.

In the drawings, the broken lines on the set of animal boots depict elements that form no part of the claim. The broken lines showing a dog depict environmental structure that that form no part of the claimed design. All broken lines form no part of the claim.

1 Claim, 7 Drawing Sheets
